UNITED STATES PATENT OFFICE

CHARLES A. JUENGST, OF CROTON FALLS, NEW YORK, ASSIGNOR TO AMERICAN ASSEMBLING MACHINE COMPANY, INC., OF MEMPHIS, TENNESSEE, A CORPORATION OF DELAWARE

BOOKBINDING MACHINE

Application filed May 14, 1921. Serial No. 469,693.

This invention relates to the art of bookbinding and has more particular reference to a process and machine for gathering signatures and sewing the signatures together to 5 form a book in one continuous operation.

One feature of the invention resides in a method and means for co-ordinating a gathering machine and a sewing machine. Other features of the invention reside in a method 10 of and means for sewing the signatures together to form a book capable of use independently of the gathering machine. The invention further resides in certain novel products obtained by the method and mechanism 15 above mentioned.

Other features of the invention appear as the specification proceeds.

Figure 1 is a diagrammatic plan view of a 20 combined signature, gathering sewing and covering machine embodying the invention.

Figures 2, 3, 4, 5 and 6 when placed end to end show a substantially continuous side elevation of a sewing machine and part of a gathering machine embodying the invention.

Figure 2 is a side elevation of the major portion of the sewing machine and the delivery mechanism.

Figure 3 is a side elevation of one end of the sewing machine and the driving means for 30 the gathering machine conveyor.

Figure 4 is a side elevation of the turning device for changing the position of the signature groups from a substantially horizontal to a substantially upright position.

Figure 5 is a side elevation showing a portion of the gathering mechanism.

Figure 6 is a side elevation partly in section of a power unit adapted to be used in connection with the machine.

Figures 7, 8, 9, 11 and 12 when placed end to end show a plan view of a combined sewing and gathering machine embodying the invention.

Figure 7 is a plan view of Figure 2.

Figure 8 is a plan view of Figure 3.

Figure 9 is a plan view of Figure 4.

Figure 10 is a sectional view on the plane of line 10—10 of Figure 14.

Figure 11 is a plan view of Figure 5.

Figure 12 is a plan view of Figure 6.

Figure 13 is a side elevation of the sewing machine looking in the direction of arrow 13 in Figure 7.

Figure 14 is a vertical sectional view looking in the direction of arrow 14 in Figure 5. 55

Figure 15 is a vertical sectional view on the plane of line 15—15 of Figure 9.

Figure 16 is a vertical sectional view on the plane of line 16—16 of Figure 8.

Figure 17 is a sectional view on the plane of line 17—17 of Figure 7 showing the change speed mechanism of the sewing machine. 60

Figure 18 is a sectional view on the plane of line 18—18 of Figure 17.

Figure 19 is a plan view of parts of the 65 change speed mechanism shown in Figure 20.

Figure 20 is a sectional view through part of the change speed mechanism on the plane of line 20—20 of Figure 17.

Figure 21 is an enlarged detail view of 70 part of the sewing machine shown in Figure 8.

Figure 22 is an end elevation of some of the parts shown in Figure 21 partly in section on the plane of line 22—22 of Figure 3.

Figure 23 is an enlarged sectional view on 75 the plane of irregular line 23—23 of Figure 25.

Figure 24 is a horizontal longitudinal sectional view through a group of needles.

Figure 25 is an enlarged sectional view on 80 the plane of line 25—25 of Figure 22.

Figure 26 is a front elevation of a portion of the needle carrier showing the needle and presser foot.

Figure 27 is a top plan view of Figure 26. 85

Figure 28 is a view in elevation looking from the right hand side of Figure 26 with the needle carrier support in section.

Figure 29 is a view similar to Figure 26 but partly in section showing the last sewing needle and the lock needle of sewing machine. 90

Figure 30 is a sectional view on the plane of line 30—30 of Figure 29.

Figure 31 is a view in elevation looking in the direction of the arrow 31 of Figure 34. 95

Figure 32 is a detail sectional view on the plane of line 32—32 of Figure 34.

Figure 33 is a sectional detail view on the plane of line 33—33 of Figure 34. 100

Figure 34 is a top plan view of Figure 31 or a view looking substantially downward on line 34—34 of Figure 35.

Figure 35 is a vertical sectional view substantially on the plane of line 35—35 of Figures 2 and 7.

Figure 36 is a detail sectional view on the plane of line 36—36 of Figures 2 and 40.

Figure 37 is a detail sectional view on the plane of line 37—37 of Figure 40.

Figure 38 is a detail sectional view on the plane of line 38—38 of Figure 40.

Figure 39 is a broken detail view of parts adjacent to crank 190 shown in Figure 40.

Figure 40 is a detail view partly in section of the parts adjacent to the last sewing needle and the lock needle and viewing the sewing table in plan.

Figures 41 and 42 are detail views of the lock loop shuttle.

Figure 43 is a plan view of the sewing machine table and throat plate.

Figure 44 is an enlarged detail view of means for adjusting the lower guide shown in Figure 43.

Figure 45 is a sectional view on the plane of line 45—45 of Figure 44.

Figure 46 is an enlarged detail elevation of portion of Figure 2.

Figure 47 is a similar view of the upper portion of the sewing machine structure with the parts broken away and in section.

Figure 48 is a vertical sectional view looking in the direction of arrow 48 in Figure 47.

Figure 49 is a vertical sectional view on the line 49—49 of Figure 2.

Figure 50 is an enlarged detail view of the cutting mechanism shown in Figure 2.

Figure 51 is a vertical sectional view on the plane of line 51—51 of Figure 49.

Figure 52 is a sectional view through the cutting mechanism on the plane of line 52—52 of Figure 53.

Figure 53 is a sectional view similar to Figure 51 but showing the cutting knives open.

Figure 54 is an enlarged sectional view on the plane of line 54—54 of Figure 49.

Figure 55 is an enlarged view in elevation looking from the left hand end of Figures 2 and 7.

Figure 56 is a sectional view on the plane of line 56—56 of Figure 55.

Figures 57 to 65 inclusive are diagrammatic views showing the method of sewing, Figures 57, 58 and 61 to 65 inclusive being diagrammatic plan views showing progressive steps and Figures 59 and 60 being sectional views on the plane of line 59—59 of Figure 58 and 60—60 of Figure 61.

Figures 66, 67 and 68 are diagrammatic plan views showing the method of forming the lock stitch.

Figures 69 to 75 inclusive are diagrammatic views illustrating the progress of the

signature and signature group through the gathering and sewing machine.

Figure 76 is a perspective view of one product that may be obtained by the invention of this application.

Figure 77 is a perspective diagrammatic view showing the chain stitches and the lock stitch used in sewing the signatures together.

Figure 78 is a vertical sectional view similar to Figure 14 but showing a modified form of the invention.

Figure 79 is a sectional view similar to Figure 37 showing a modified form of the invention.

Figure 80 is a view looking in the direction of arrow 80 of Figure 79.

Figure 81 is a view similar to Figure 43 showing a modified form of the invention.

Figure 82 is a distorted diagrammatic view showing the method of tipping single sheets to folded signatures and of conveying the thus combined signatures to a needle in the sewing machine.

Figure 83 is a detail view showing the adjustable crank 56 of Figure 12.

Figure 84 is a view somewhat similar to Figures 14 and 78 showing a modified form of the invention in which glue is applied to the signatures while being gathered.

Figures 85 and 86 are perspective views showing different products that may be obtained by the invention of this application.

Before proceeding to a detailed description of the method and machine embodying the invention, it will be best to consider in a general way the steps performed in gathering the signatures and binding the book in accordance with this invention. Referring to Figures 69 to 75, each signature 1 in being deposited into the raceway from the hopper containing the signature stack is subjected to the action of an opening device that separates the halves of the signature, and while thus separated, the signature is progressed longitudinally of the machine to bring a guide between the halves of the signature and is then progressed still further longitudinally and associated with other signatures side by side by piling one signature on top of another or by on-setting the signatures with respect to each other and this operation is continued until a group of signatures of sufficient number is produced, each of which signatures has a separating member or guide inset between the halves thereof. The signature group is then turned into a substantially upright position with the folded backs of the signatures lowermost, and the signature group is then advanced in this position along said guides until it reaches the sewing machine where the guides terminate at the point where the needle bars are located.

These needle bars pass down into center of each signature and stitch through the folded backs of each signature and by means of looping devices associated with these needle bars

79

chain stitches are formed between the several signatures of the same group and the aligned signatures of successive signature groups or signatures in tandem are also sewn together, after which a cutting mechanism acts to sever the threads between successive signature groups or signatures in tandem and the completed book is delivered into a suitable delivery or it may be carried directly to a covering machine where the cover will be attached.

The general character of the product that may be obtained by this method and machine is shown in Letters Patent Nos. 893,512 and 893,513, both dated July 14th, 1908, and the specific product that may be obtained in the particular form of sewing machine here disclosed as one exemplification of the invention is shown in Figure 76.

The general arrangement of the several devices with respect to each other is shown in Figure 1, in which 2 indicates the gathering machine, 3 the sewing machine and 4 the covering machine.

Referring particularly to Figures 4, 5, 9, 11, 14 and 15, the gathering mechanism consists of the usual series of hoppers 5 in which the signatures are stacked and suitable means are provided for removing the signatures from the hoppers such as suckers 6, which pull down the folded end of the signatures from the pile in the usual way, and grippers 7, mounted on rock shaft 8, which swing back and forth and seize the lowermost signatures in the hoppers and carry them out and drop them on a raceway generally designated by the reference character 9. The raceway consists of a lower compartment 10 and a series of overlapping ledges or vanes 11 which constitute a false bottom in the raceway. There is a slot 12 both in the lower compartment and in the false bottom through which project pins 13 mounted on a conveyor chain 14 such as is generally employed in gathering machines. Each gripper 7 deposits a signature on false bottom 11 and immediately thereupon a suction member 15 mounted on rock shaft 16 descends into contact with one of the free corners of the signature and effects a preliminary separation of the two halves thereof as indicated diagrammatically in Figure 69. Immediately thereafter a separating blade 17 (Figures 69 and 70) moves longitudinally of the signature and effects a more complete separation of the two halves thereof. Pin 13 on the gathering machine conveyor then moves the signature longitudinally of the machine (Figure 10), and in so doing brings the separated halves of the signature into a straddling position with respect to the next successive ledge or vane 11. It will be noted from Figure 10 that said vanes or ledges have a slight downward incline in the direction of movement of the signature so as to eventually bring the signatures into

superposed relation in lower compartment 10. When pin 13 has brought a signature into straddling position on a vane 11 the next succeeding signature will be superposed by the next gripper 7 on top of one half of said first signature. Figs. 10 and 71 show a signature in straddling position on one of the vanes 11 and ready for the next signature to be superimposed thereon. Connected to the lower end of each vane 11 is a guide that continues from that point to a needle bar guide in the sewing machine. In this instance an ordinary wire 18 extends from each vane 11 to a needle bar guide 19 (see Figure 24), so that the signatures of each group has its halves maintained separated until the sewing has been performed. The preliminary separating blades 17 are mounted on a slidable shaft 20 carried in suitable brackets 21 and reciprocated by means of arm 22 secured by means of slotted connection 23 with said shaft 20 and in turn mounted on shaft 24 on which is carried a bevel gear 25 to which an oscillating motion is imparted by means of a gear sector 26 mounted on stub shaft 27 and rocked by means of cam 28 engaging cam roll 29, said cam 28 being mounted on the main shaft 30 of the machine. A spring 31 connects arm 22 with the frame work of the machine and serves the function of keeping cam roll 29 in engagement with cam 28. Any suitable means may be employed for rocking suction member 15. In this instance said member is carried by rock shaft 16 provided with an arm 32 connected by link 33 to rock arm 34, roller 35 of which is engaged by cam 36 on the main shaft, said roller being held in engagement with said cam by the action of spring 37 connecting arm 32 with the frame work of the machine. The means for actuating suckers 6 and gripper 7 are not shown since these devices are well known in the art in the well known Juengst gathering machine.

The means for producing suction in suckers 6 and 15 may take many forms but are preferably constructed as follows:

Referring to Figures 6 and 12 main shaft 30 is connected with a suitable power transmission mechanism here shown as motor 38 having a belted drive to shaft 39 said shaft having a pinion 40 engaging gear 41 on shaft 42 which latter carries a pinion 43 engaging spur gear 44 on crank shaft 45. Motion is imparted from this crank shaft to the main shaft by means of bevel gears 46. 47 is a suction cylinder having a plunger or piston 48 connected to a crank pin 49 by means of rod 50. Cylinder 47 has a plurality of apertures 51 connected by suitable flexible connections 52 (see Figure 14) to hollow shaft 53 connected to sucker 6 by a flexible connection 54. Similarly 55 is second cylinder operated from crank 56 by means of connecting rod 57 and having a plurality of

apertures 58 connected by flexible connections 59 to a hollow shaft 60 (see Figure 14) which in turn is connected to opening member 15 by means of flexible connections 61. The internal construction of cylinders 47 and 55 is alike and is shown in section in Figure 6. Taking one as an example of both, piston 48 reciprocates in the cylinder and on the stroke to the left in Figure 6 effects opening of check valve 62 after it passes apertures 51 so as to prevent an accumulation of pressure in the closed end of the cylinder and on its stroke in the right hand direction in Figure 6 creates a suction through apertures 51 and until the end of piston 48 approaches the end of its stroke in a right hand direction, when, owing to the cutout portion 63 in cylinder 47 and aperture 64 in the piston a quick release of the suction is obtained by the ingress of air. It will be understood that cams 36 and 28 are adjustable so as to obtain the proper timing of the parts and so likewise the member on which crank pin 56 is mounted is adjustable as shown in Figure 83. In this figure bevel gear 46 mounted on shaft 45 is provided with an adjustable member 65 provided with arcuate slots 66 and bolts 67 whereby said member 65 may be adjusted circumferentially with respect to shaft 45. Formed integrally with adjustable member 65 is a crank arm 68 carrying crank 56 and a casting comprising member 65 and crank arm 68 is split as shown at 69 and clamped to the shaft 45 by means of bolt 70.

In the form of the invention shown in Figure 14 it has been assumed that the signatures are provided with closed heads since otherwise there would be no certainty that sucker 15 would separate the signatures at their middle portion. When signatures with open heads are used it is convenient to employ the expedient shown in Figure 78. In this figure suckers 15 are omitted or they may simply be rendered inoperative as will be understood and reciprocating shaft 20 is also rendered ineffective as by removing separating blades 17. When open head signatures are used it is proposed to fold the signatures off center so that one half of the leaves will be wider than the other half. By mounting adjacent to each ledge or vane 11 a supporting member 71 which may be carried by a rod as 72 it will be understood that when gripper 7 drops the signature with the short side of the signature lowermost said short side will fall on ledge 11 but that the upper side will fall on supporting surface 71 as indicated in Figure 78 and that a separation of the two halves of the signature will thus be effected. After this occurs pin 13 on the conveyor chain will then move the signature longitudinally and cause it to straddle the next succeeding ledge 11.

As shown more particularly in Figures 4 and 15 the vanes or ledges 11 terminate a short distance beyond the last hopper of the gathering machine but lower compartment 10 continues and forms a suitable means not merely for supporting the signature group but also for the purpose of turning the said signature group from a substantially flat position into a substantially upright position and to this end said lower compartment takes the form of a spiral as shown more particularly in Figures 4, 9 and 15 and the gathering machine chain 14 is likewise given a twist so that pins 13 are gradually turned from a more or less upright position to a more or less of a horizontal position, or the turning device may be of a different character, such, for instance, as shown in Patents 846,923 of March 12th, 1907, and Reissue 13,967 of August 24, 1915. In the present case gathering machine chain 14 is driven from sprocket 73 and, at the other end of the gathering machine, passes over an idler sprocket not shown. Raceway 9 is provided with a guide 74 (Figure 14) so inclined as to present pins 13 at the proper angle to the flatwise disposed signatures during the major portion of its travel through the gathering machine and at the end of the gathering machine as shown more particularly in Figures 4, 9 and 15 said guide 74 is of spiral formation to correspond to the similar spiral formation of the sidewalls of lower compartment 10.

From the foregoing it will be understood that the signature groups advance after passing through the spiral turning device in an upright position with their folded backs lowermost sliding on an extension of sewing table 75 of the lower surface of lower compartment 10, being advanced by pins 13 (see Figure 16) and that side guides 76 are provided for maintaining the signature group in this upright position; that nevertheless the halves of each signature of the group are maintained separated by reason of wires 18 extending from the separating devices of the gathering machine to the needle bars of the sewing machine. At a certain point in their forward travel over the surface 75 (see Figure 16) the signature group passes out of control of the gathering machine conveyor pins 13 and come under the control of the sewing machine conveyor 77 provided with pins 78, and this conveyor carries the signature group through the sewing machine. Sewing machine conveyor 77 is driven by sprocket 79 (see Figures 2 and 7) and returns over an idler 80 (see Figures 3, 8 and 16).

In the particular form in which the sewing is accomplished in the present instance it will be understood from Figures 76 that the needle descends through the first signature 81 and that a loop is formed that is carried

beneath the second signature 82 and that the second needle descends through the loop thus formed thereby producing the chain stitch shown in Figure 77 from one signature to another thus sewing them together. Thus the same needle will make a number of stitches in the same signature but a different needle will be used for each signature and the needle that acts upon the second signature must act later than the needle that pierces the first signature so that said second needle will not only pierce the signature but will also pass through the loop extending from the first needle beneath the second signature. As it is desirable to have the chain stitches that extend from one signature to another extend transversely across the signature group in a straight line substantially parallel to the top and bottom of the signature group it will be understood that it is either necessary to arrange the needles obliquely with respect to the incoming signature group or else that the incoming signature group advance obliquely with respect to a series of needles arranged in a straight line one behind the other. In the present instance it is preferred to mount the needles in a straight line one behind the other and accordingly as will be seen from Figures 35, 46, 43, 24 and 7, there is a plurality of needle bars 83 mounted on a needle bar carrier 84 (see Figures 31 and 13) and these needle bars as will be seen from Figures 26 and 38 and 24 are provided with slides 85 preferably of wedge-shape formation and these slides extend into and are confined by similarly shaped guides 19 to the tip end of each of which is attached a wire 18 leading from vanes 11 of the gathering machine and which as before described serve to keep the halves of each signature separated to a very slight extent. The signatures therefore in advancing over wires 18 are finally caused to straddle guides 19 and slides 85 thereby insuring the descent of the needle bar into the gutter or middle portion of a signature with which it is intended to co-operate. At the lower end of each needle bar is a needle 87 (see Figures 26 and 28) and a presser foot 88 said needle being removably and adjustably secured to the bar by means of set screw 89, and the presser foot 88 is in the form of a wire loop extending from said bar and bent back upon itself so that the free end thereof returns into the needle bar and is yieldably held by means of spring 90; said presser foot is secured in position by means of nuts 91 at the upper end of the needle bar and by this device proper adjustment of said presser foot may also be obtained. The needle bar carrier 84 is supported by two cranks 92 (see Figures 2, 18, 35, 31 and 33) and these cranks are mounted on shafts 93. Shafts 93 are each carried by two arms 94 mounted on rock shafts 95. Loosely mounted on shafts 95 are

spur gears 98, keyed to the hub of bevel gear 97 meshing with bevel gear 96 (see Figure 18). Meshing with spur gears 98 are spur gears 99 keyed to shafts 93. At the end of shafts 93 are cranks 92 secured in position by means of a clamp 100 and bolt 101. 102 indicates the crank pin carried by the crank and extending into a bushing 103 forming part of a bracket 104 secured to the needle bar carrier 84. Mounted on one of shafts 93 (see Figures 31, 32, 33 and 34) is an eccentric 105 secured to said shaft by means of a key 106. 107 is an eccentric bushing carried by arm 108 pivotally supported on stud 109 mounted in stationary bracket 110.

By the foregoing means the orbit shown in Figure 26 at 111 is obtained. This is accomplished by the combined action of the two cranks 92 and the eccentric 105 and causes arms 94 to rock on centers coincident with shafts 95. It will be apparent that if eccentric 105 and its anchored connections were not provided the needle bar carriage and consequently the needles would describe a circular orbit which is undesirable because the needle would then enter and leave the paper in a somewhat pronounced curved path and since the signature is fed forward with a variable motion, that amounts almost to an intermittent motion, and are practically, and may be absolutely, in a state of rest, at the time the needle enters and leaves, it is necessary to flatten the orbit of the needle, so to speak, in order to prevent relative displacement between the needle and paper and consequent tearing of the latter. The cranks 92 and the eccentric 105 are therefore so timed circumferentially with respect to each other that, when the cranks tend to move the needle bar carriage sideways, the eccentric 105 will compensate to some extent for this movement but will not interfere with the up and down stroke imparted by the cranks because of rocking motion of arm 108 on stud shaft 109. Only one eccentric is needed because the needle bar carriage forms a connection between the two shafts 93. Guides 19 in which the slides of the needle bars operate are mounted on a bar 112 adjustably supported in the following manner: Mounted on the sewing table 113 are two uprights 114 on which are vertically adjustable collars 115. These collars are provided with openings 116 into which extend rods 117 adjustable toward and away from the needles and secured in position by means of bolts 118. To the inner end of rods 117 is bolted connecting bar 112. It will be observed that, during the downward stroke of the needle bars, slides 85 (see Figures 26 and 24) will extend into the narrowed portions of guides 19 and will thus tend to center the needles with respect to the gutter of the signature.

Referring to Figures 2, 3, 7, 8, 13, 21, 22, 23, 25, 35, 47 and 48, 119 indicate side frames 130

of the sewing machine between which extend two cross bars 120 and 121 occupying different levels in the machine. Mounted upon these cross bars are two sets of spool supporting spindles 122 and 123 arranged in staggered spool relation as shown more particularly in Figures 7 and 35. Mounted on end frames 119 are three sets of upright posts 124, 125 and 126 between the members 10 of each set of which extend rods 127, 128 and 129. Threads are led from the spools on spindles 122 through pigtails 130 carried by rods 127 and thence over rod 129 while threads coming from spools on spindles 123 are led 15 over pigtails 132 of rod 128 and thence over rod 129. The threads from both sets of spools then pass from rod 129 through pigtails 133 and thence through tension device 134^a. From this point each thread passes through 20 an eye in detector lever 134 thence through pigtail 135 thence through pigtail 136 on the back of a needle bar (Figure 28) and thence through the eye of the needle. The tension devices are mounted upon a cross bar 137 extending across the front of the machine between the end frames 119 and the detector levers 134 are mounted upon cross bar 138 also 25 extending across the machine between the end frames at a point just below cross bar 137.

30 Each tension device consists of a spindle 139 slidably mounted in bar 137 and having at its outer end a head 140 and adjacent thereto a washer 141 the thread being pinched between the head and the washer. At the back 35 side of frame 137 there is loosely mounted upon said spindle a flanged collar 142 against which presses a spring 143 the tension of which may be adjusted by a knurled head 144. Extending across the machine is a rocking 40 member 145 pivotally supported at 146 in the end frames of the sewing machine and this rocking member has at one end a lever 147 to which is connected a link 148 attached at its other end to a rocking lever 149 actuated 45 by means of cam roller 150 from cam 151 mounted on one of the shafts 93. The action of cam 151 causes, through the connections described, a rocking movement of rocking member 145 and by engagement of the latter 50 with flanged collar 142 spring 143 is compressed thereby pulling spindle 139 rearwardly through frame 137 and causing the thread to be pinched between head 140 and washer 141. The reverse movement of member 145 releases the tension on the thread, cam roller 150 being kept in engagement with cam 151 by means of spring 152. One rocking member 145 actuates all the tension devices 55 and constitutes in effect a series of bifurcated 60 arms extending into flanged collars 142, said rocking member being to that end provided with a series of notches 153^a (see Figure 47) into which flanged collars 142 project.

Means for detecting the breaking of a 65 thread are constructed as follows: Mounted

upon the transverse brace 138 are a series of brackets 153 which are bifurcated at the outer ends to afford bearings for spindles 154 on which are hung detector arms 134. 155 is a spring that presses on each detector arm 134 and normally tends to urge it into the dotted line position shown in Figure 23. The tendency of this spring to urge the arm 134 into said dotted line position is normally neutralized by reason of the thread which passes over stationary guide pins 156 and through eye 157 in said detector arm. Brackets 153 form guides for a reciprocating member 158 that extends in the rear of arms 134 and which normally reciprocates at all times. Said reciprocating member is provided with a notch 159 corresponding to each detector arm 134 and so long as the thread remains unbroken said detector arms are held out of engagement with said reciprocating member but when a thread breaks the detector arm corresponding thereto will be urged by spring 155 into engagement with notch 159 of the reciprocating bar and will arrest the movement of the latter. 160 indicates an upright oscillating shaft driven from cam 161 (Figures 3 and 8) by means of horizontal arm 162 connected to the lower end of said upright shaft 160 and carrying at its other end a cam roll 163 that engages said cam 161 on main shaft 30. Connected to the upper end of said oscillating shaft 160 (Figures 21, 22 and 25) is an arm 164 connected by means of lever 165 and link 166 to reciprocating member 158. 167 indicates a spring connecting the free end of lever 165 with arm 164 and normally moving said lever 165 against the stop 168, the effect of which is, under normal conditions, to make arm 164 and lever 165 a rigid connection to link 166. When however reciprocation of member 158 is arrested arm 164 will continue its oscillating movement but since this movement can no longer be transmitted to member 158 lever 165 will swing around pivot 169 against the action of spring 167 and will press button 170 thereby stopping the machine. The details of the stopping device are not shown since such devices are well known; for instance, the well known Cutler-Hammer electrical stopping device can be used for this purpose; and the effect of pressing button 170 will be to stop motor 38 or rotation of main shaft 30, depending upon the character of drive used thereby stopping both the gathering and the sewing machine.

Referring to Figures 35, 40, 46, 36, 39, 38, 2 and 7, 171 indicates a plurality of rotatable looping members each of which consists of a spindle 172 provided with a head 173 at its upper end slotted to receive a double looper 174 having oppositely facing looping surfaces 175 each of which surfaces terminates in oppositely disposed points or tips 176. Each spindle 172 is mounted in a bushing 177 suitably supported as by means of a bracket 178

secured to the under surface of sewing table 113. In the present construction there is a bracket 173 for each looping member and these loopers are so positioned as to be beneath the throat plate 179 and needles 87. Suitable means are provided for driving the rotatable looping member in this instance comprising (Figure 13) a spur gear 180 meshing with one of gears 98, said spur gear 180 being mounted on a shaft 181 carrying another spur gear 182 meshing with spur gear 183 which in turn drives shafts 184 by meshing with spur gear 185; said shaft 184 extending across the machine (Figure 7) and carrying at its outer end a bevel gear 186 meshing with a bevel gear 187 on stub shaft 188. 189 indicates a looper drive shaft common to all the looping devices. This shaft 189 is driven from shaft 188 with a variable motion, almost amounting to an intermittent motion, the means here used being what are commonly called a Whitworth motion, shown more particularly in Figure 39 in which 190 indicates a slotted crank arm mounted on the end of shaft 188, and 191 is a crank mounted on shaft 189 and carrying a roller 192 that extends into the slotted crank 190. Shaft 189 is provided with a plurality of spiral gears 193 which mesh with corresponding spiral gears 194 mounted on spindles 172 of the looper. 195 is a lock loop shuttle slidably mounted in one of the brackets 196 carrying the looper drive shaft 189. This shuttle is free to move in either direction but its movement is limited at one end by fixed stop member 197 and the shuttle is actuated at suitable intervals in the other direction by means of actuating arm 198 pivotally supported on pivot 199 and actuated by means of cam roll 200 from cam 201 carried on shaft 184.

Referring to Figures 43, 44, 45, 46, 36, 39, 2 and 7, 179 is a throat plate extending beneath the needle bars and above the looping devices, being suitably supported in the sewing table 113 and flush with the upper surface thereof. Said throat plate is in the present instance composed of two members, one 202 which is stationary and the other 203 which is movable. Member 203 is composed of a series of plates as shown in Figure 43 secured to a common support 204 slidably mounted in the sewing table and is actuated by means of two upright arms 205 mounted on a shaft 206 said arms having bifurcated upper ends as shown that engage blocks 207 on rod 208, said rod 208 being mounted on brackets 209 one at each end of the common support 204. Shaft 206 is rocked by means of arm 210 having a cam roll 211 engaging cam 212 mounted on stub shaft 188. A spring 213 connected between the arm 205 and a stationary part of the machine holds cam roll 211 in engagement with cam 212. Guides 76 terminate approximately at the point where the sewing machine structure begins. Arranged oblique-

ly with respect to the straight line in which the needles are located are upper book guides 214 and 215 and lower book guides 216 and 217, the latter arranged adjacent to the throat plate and likewise inclined obliquely with respect to the line of needles; these book guides acting to present a signature group obliquely with respect to the line of needles so that successive needles will engage successively successive signatures of an advancing group. Lower guide 217 is carried by two slotted arms 218 into the slots of which extend threaded stems 219 seated in the sewing table, knurled heads 220 acting as clamping members to bind the slotted arms 218 into the position to which they may be adjusted. The other lower book guide 216 is pivotally supported at one end on pivot 221 carried by one of the plates making up the member 203 of the throat plate, the other end of said lower book guide 216 being adjustably secured in slot 222 in the sewing table by means of a slidable member 223 seated in said slot 222 and pivotally connected to lower book guide 216 at the point 224, said slidable adjustable member 223 being secured in the position to which it has been adjusted by a clamping means such as screw 225. It will be understood that as member 203 of the throat plate is reciprocated at intervals by cam 212 lower book guide 216 will rock around pivotal center 224 and will thereby crown the signature group against the stationary lower book guide 217. Upper book guides 214 and 215 terminate substantially at the end of the sewing machine structure and from this point on the signature groups are held in position by guides 226 (Figures 2 and 7). Guides 76, 214, 215 and 226 are mounted in any suitable manner upon the supporting structure of the machine such as by means of upright posts 227 having vertically adjustable collars 228 which afford an adjustable supporting means for the stem 229 of said guides. Both the collars 228 and the stems 229 are secured in position after adjustment is made by means of binding screws 230 and 231. It will be understood that by these means the guides may be adjusted to various widths and thicknesses of books that are to pass through the machine and that the adjustment of lower book guide 217 by means of slotted arms 218 is for the same general purpose. As a modification of the foregoing construction there is shown in Figures 79, 80 and 81 a throat plate 179 the members of which are stationary with respect to each other instead of being movable as in the first described construction. In this case lower book guide 216^a is pivotally supported at pivot point 232 on throat plate 179 and the forward end of said lower book guide 216^a is connected by means of a bent rod 233 extending through a slot 234 in the throat plate to a block 235 pivotally con-

nected to upright arm 236 mounted on shaft 206. Block 235 is adjustably connected to the bent connection 233 by means of two nuts 237 in engagement with the threaded portion of said bent connection and arm 236 is actuated by means of connection 238 carrying a cam roller 239 engaging cam 240 on the stub shaft 188. It will be noted that in this case cam 240 is displaced circumferentially 180 degrees with respect to the position shown in Figure 37 on account of the reversal of location of the pivot point of lower movable book guide.

It will be understood that pins 13 of the gathering machine conveyor and consequently the heads of successive signature groups are spaced equal distances apart, and that therefore when gathering eight inch books the spacing between adjacent books or signature groups will be different than when ten or twelve inch books are being gathered. In order to obtain proper operation of the sewing machine there must always be a signature beneath the needle when it descends, or in other words an idle movement of the needles between successive signature groups must not take place. It is therefore necessary to make the spacing of adjacent successive signature groups substantially alike, regardless of the size of the book that is being handled, and it follows that the signature groups must be justified so to speak with respect to each other after leaving the gathering zone and before entering the sewing zone. It will also be understood that in the present form of the invention there will be a given number of signature groups, say sixty per minute, delivered from the gathering machine regardless of whether eight, ten or twelve inch books are being gathered and that it will therefore be necessary when sewing the larger size books that the sewing machine run at a greater speed than when smaller books are being sewed, if the same product is to pass through the machine in a given time regardless of the size thereof. To bring about a proper spacing of the books or signature groups before they enter the sewing zone and to vary the speed of the sewing machine so as to maintain a constant output of product regardless of the size of the latter, the following means are provided:

Referring to Figures 3, 8 and 16, gathering machine conveyor 14 is driven from sprocket 73 keyed to stub shaft 241 carrying at its outer end a bevel gear 242 which is driven from main shaft 30 by means of spur gear 243 mounted on said main shaft and engaging the corresponding spur gear 244 carrying a crank 245 in the form of a link pivotally supported on said gear 244 and connected with a crank 246 mounted on the end of stud shaft 247 which latter is provided with a bevel pinion 248 meshing 65 with bevel gear 242 on shaft 241. This

construction is what is generally called Whitworth motion and introduces a variably continuous motion not unlike an intermittent motion. The sewing machine conveyor 77, Figures 2, 3, 7, 8, 13 and 16, is driven from sprocket 79 at one end and passes over idler 80 at its other end, the upper run of said conveyor passing over the sewing table and throat plate as indicated in Figures 36 and 39 and the lower run passing beneath the sewing machine structure proper. Idler 80 is loosely mounted on stub shaft 241 and sprocket 79 is keyed to shaft 249 extending beneath the machine and having at its outer end slotted disc 250 which latter is driven by means of two pins 251 on shaft 184 carrying gear 185. The engagement of pins 251 with the slotted disc 250 produces a variably continuous motion not unlike an intermittent motion. The speed of sewing machine conveyor 77 is at all times somewhat greater than the speed of gathering machine conveyor 14 so that the signature groups in being transferred from the control of the gathering machine conveyor to that of the sewing machine conveyor may be spaced substantially uniformly with respect to the distance between successive signature groups. The most common sizes of books produced in the art are eight, ten and twelve inch books and in order to adjust the machine to operate properly on books of different size a change speed mechanism is provided whereby the speed of the needle bars, the speed of the sewing machine conveyor, the speed of the looper members, the frequency of the operation of lock stitch shuttle 195 (Figure 40) and the frequency of operation of the movable member of the throat plate, may all be varied so as to maintain all the movable parts of the sewing machine in synchronism under varying conditions. In the present instance the change speed mechanism takes the following form (see particularly Figures 13, 17, 18, 19 and 20). Meshing with bevel gears 97 that are keyed to spur gears 98 are bevel gears 96. These bevel gears 96 are keyed to shaft 252 carrying a spur gear 253 having a very wide face. Suitably mounted in swinging brackets 254, pivotally supported on a center coincident with shaft 252 are three spur gears 255, 256 and 257 all keyed to sleeve 258 which latter is slidably mounted on shaft 259 carried at the lower end of brackets 254. Mounted on main shaft 30 and connected thereto by means of a suitable clutch 260 is a spur gear 261. It will be understood that spur gear 255 is always in mesh with wide faced gear 253 but that by sliding sleeve 258 on shaft 259 either one of the gears 255, 256 or 257 may be brought into mesh with spur gear 261 on the main shaft. In order to compensate for the difference in diameter of the three change speed gears, brackets 254 are swung around center 252 until the proper 130

center distances are obtained between main shaft 30 and shaft 259 when changing from one speed gear to another.

In order to maintain brackets 254 in the proper position to which they have been adjusted there is provided on a stationary part 262 of the machine a slot 263 through which extends a stem 264 provided with a nut 265. For the purpose of easily ascertaining the requisite distance it is necessary to slide sleeve 258 an actuating member 266 is provided which slides in the lower end of one of the brackets 254 and has connection with a grooved collar 267 forming part of sleeve 258. Member 266 is provided with notches 268 which register with a latch 269 said slots 268 being so positioned with respect to this latch that when the latch enters a certain slot a certain intermediate gear will be properly positioned sidewise with respect to spur gear 261 on the main drive shaft. It will therefore be understood that by adjusting the change speed mechanism all the operating parts of the sewing machine are adjusted in synchronism to correspond to a given size of book. In addition, however, to changing the speed of the parts it is necessary to adjust the spacing between pins 78 of sewing machine conveyor 77. As an instance of how this may be done we may assume that conveyor 77 has one hundred and twenty links and that each link has provision for supporting a pin 78. In the case of eight inch books said chain would be provided with thirty pins; in the case of ten inch books with twenty-four pins; and in the case of twelve inch books with twenty pins. This would with a given change in speed above that of the gathering machine conveyor 14 provide a spacing between the books in the sewing machine conveyor of respectively one, one and a quarter and one and a half inches for eight, ten and twelve inch books. The distance between the needles of the sewing machine or between successive piercings of the same needle is in this case two and a quarter inches and the relation between the parts will therefore work out in such a way that the eight inch book would be pierced four times by each needle, the ten inch book five times, and twelve inch books six times, with no intervening descent of the needle between successive signature groups. It will be understood that these proportions are given merely by way of example, the object being to show that the signature groups in passing from the gathering machine conveyor to the sewing machine conveyor are justified or spaced as to distance between successive signature groups in such a way that they are a less distance apart than the distance between successive piercings made by the same needle in the same signature and that the number of stitches is so varied as to produce a greater number of stitches in the larger books than

in the smaller books and that there would be no descent of the needle in the space between successive signature groups or signatures in tandem, the size of the stitch being the same. In this connection it may be stated that the signature group is practically at a standstill when the needle leaves the paper and obtains its highest speed at the bottom of the orbit and at the top of the orbit of the needle as shown in Figure 26 and that the speed of the needle and the speed of the conveyor are substantially the same, at least while the needle is traveling through its lower orbit with the advancing signatures. This is effected by reason of the two pins 251 (Figure 13) mounted on shaft 184 said shaft making one revolution to each complete orbit of the needle, so that the sewing machine conveyor 77 makes in effect substantially two forward intermittent movements during one orbit of the needle.

In starting the machine it is desirable to fill the machine with books before the sewing operation commences. Any suitable expedient may be used to obtain this result, for instance, (Figure 13) clutch 260 connecting the main drive shaft with the sewing machine may be released and pins 251 may be removed and a crank attached to the end of shaft 249 so that the books may be conveyed through the machine from one end to the other before sewing commences. So also the automatic stopping device may be electrically disconnected.

Referring to Figures 57 to 65 inclusive and 76 and 77 there is shown a series of diagrams to indicate one preferred method of sewing the signatures of the same group together. The signature group "C" is advanced obliquely with respect to the line of needles 87 and as the first signature 81 of the group comes beneath needle 87 it pauses and comes almost to a stop at which time said needle will pierce the gutter of said signature 81 and said needle then passing through its lower orbit (Figure 26) will immediately thereafter travel at its greatest speed which will be substantially that of the advancing signature group the speed of which latter is also accelerated at the same time. This is shown in Figure 57. The forward movement of the book and needle, during the lower part of its orbit, brings the book into the plane of the orbit of the looper element or wing 174. As the needle leaves the paper the forward motion of the signatures practically ceases and substantially at this time the needle has reached the point of intersection with looper element 174 and as the needle rises out of the throat plate 179 it forms a loop "B" (see Figures 58 and 59) and the tip 176 of the looper member 174 engages said loop (Figures 60 and 61). After this has happened the forward motion of the book is again accelerated, the needle pass-

ing through the top part of its orbit (Figure 26), and the forward motion of the signature group C pulls the thread through the needle eye and off the spool. The needle is now in the upper part of its orbit with respect to the throat plate and is out of the book as indicated in Figure 62. The movable member 203 of the throat plate has now moved back and the looper element has moved about a quarter of a revolution from the point where it engaged the loop and loop "B" has now reached its greatest length as seen in Figure 62 extending from the point of piercing "D" in the first signature around the entire length of one of the wings of the looper said loop being formed from the slack of the first needle. The tension device is now active and prevents the first looper from pulling any thread off the spool. This is not of significance as regards the first needle but the object of applying the tension device at this time in the cycle of operation will appear later. As shown by Figure 63 movable member 203 of the throat plate now moves toward the signatures and approximately at this time the second needle 87^a descends into the second signature 82. At this time the looper element 174 has rotated to the position indicated in Figure 63 and has now formed a triangular loop extending from the pierced portion "D" of the first needle in the first signature 81 which piercing is now at a point above tongue 270 of the throat plate, the loop extending around one side of said tongue 270 to one end of the looper element 174 along the same and thence back to the edge of tongue 270 and pierced portion "D." The advantage of the movement of movable member 203 of the throat plate is shown in this Figure 63 because had this movement of member 203 not occurred the loop "B" would not be so wide in the plane of the second needle 87^a and would therefore render the device less positive in action. This is indicated by the lines of small dots, which show the size of the loop if member 203 was stationary. Simultaneously with this action the first needle 87 has of course descended a second time through the first signature 81 and has produced a stitch "E" lengthwise of and within the signature. During the rotation of the looper element 174 through the next few degrees the first loop "B" is sliding along tongue 270 and is approaching a cast off position. At this moment (Figure 64) a second loop B' is being formed by the first needle 87 and being taken by the looping element 174^a and the second needle 87^a is at this time also forming a loop B² which is being taken by looping element 174^b of the second looping device. It will be understood that the loop B² formed by the second needle 87^a is now within the first loop "B" which latter is still around needle 87^a, tongue 270 and looper

element 174. As shown by Figure 65 the loop B', now being enlarged by the rotation of moving member 174^a, is pulling loop B off the first looping element 174, the latter being now in a position circumferentially where such action is possible, and, because the tension device is at this time active, as previously described, looping element 174^a cannot draw any thread off the spools and must therefore pull the previously formed loop "B" tight because both loops are in the same thread.

Referring to Figures 76 and 77 it will be understood that loop "B" forms a chain stitch extending sidewise from signature 81 to signature 82 being held by the first loop B² of the second needle 87^a in the second signature 82 and that this operation continues until all the signatures have been sewn together each needle making a number of stitches in each signature depending upon the length of the signature so as to form a plurality of chain stitches across the signature group. It will further be understood that a longitudinal stitch E' is formed between alined signatures of successive signature groups or signatures in tandem so that in effect successive signature groups or signatures in tandem are sewed together by longitudinal stitches. At a later point of operation of the machine, the threads between successive signature groups or between alined signatures of successive signature groups or signatures in tandem are severed.

Various means may be provided for locking the series of chain stitches that are produced across the signature group from one signature to another. One form of the invention contemplates the use of a so-called locking stitch to anchor the last sewing stitch in the last signature, and this form of the invention is shown in Figures 29, 30, 40, 41, 42, 46, 66, 67, 68, 76 and 77. The last needle bar of the series carries, in addition to the sewing needle previously described, a locking needle 271 that is constructed in all respects the same as the sewing needles 87, the only difference being that the last sewing needle 87 and the lock needle 271 are somewhat closer together than adjacent sewing needles. The last sewing needle and the lock needle 271 being mounted on the same needle bar 83^a as shown in Figure 29 co-operate with the same guide 19^a (Figure 46) and both act on the same signature, that is the last signature of the signature group. When the last sewing needle 87 makes its first stitch in the last signature 272 the loop formed by said sewing needle is carried around by the last looping element 273, which, owing to the fact that the needles 87 and 271 are closer together than the series of sewing needles, is of smaller length (Figure 66) and therefore travels in a smaller orbit so as to bring the loop of the last sewing needle into the plane of the locking needle 130

271. The object of having the last sewing needle and the locking needle closer together than the series of sewing needles is to avoid having the locking needle descend through the previously formed opening of the last sewing needle. As shown in Figure 66 after the last sewing needle has made its first stitch in the last signature 272, and looper 273 has carried the loop around into the plane of the locking needle 271, the first point of piercing by the last sewing needle in the last signature 272 will be in the place indicated by 274 and will be slightly offset from the point where the locking needle 271 makes its first descent into the last signature of the group as shown at 271. 275 indicates the first loop in the last signature produced by the last sewing needle and the last looping device, and it will be seen that the locking needle 271 descends on its first piercing of the last signature of the group through the first loop thus formed by the last sewing needle in the last signature, and that when looper member 276 proceeds to form the second loop of the last sewing needle in the last signature as shown in Figure 67 and thereafter proceeds (Figure 68) to cast off loop 275 that said first loop 275 will be prevented from being pulled out of the signature by reason of loop 277 formed by the lock needle and which extends through the first loop 275 made by the last sewing needle. At the time that the loop 277 is formed by the lock needle the signature group has advanced to a point as shown in Figure 68 where it is adjacent to tip 278 of locking shuttle 195 and at this moment arm 198 is actuated by cam 201 and gives the shuttle a slight movement in a direction opposite to that of the advancing signature group and away from stop 197. Said tip 278 of the shuttle 195 projects sidewise towards the needle so as to readily enter the loop formed by the locking needle and is so shaped that the loop may readily move over the same. The locking needle now ascends out of loop 275 and during the continued advancing movement of the signature group loop 277 is carried along the shuttle, while loop 275 is being drawn tight by looper 276, one position being indicated at 277^a and is slightly enlarged as the locking needle ascends so as to make certain that said loop will project a sufficient distance through last chain stitch 275 as indicated more particularly in Figures 76 and 77 to positively hold the said last chain loop 275 and prevent it from pulling through. When arm 198 is retracted by cam 201 shuttle 195 which is mounted to slide loosely in support 196^a will move with the advancing signature group until it comes in contact with the stop 197. Eventually loop 277 will reach the position indicated in Figure 68 at 277^b and upon a succeeding actuation of the shuttle by lever 198 and subsequent withdrawal thereof and before the shuttle again encounters stop

197 said loop 277^b will slip off the shuttle.

In Figure 85 is shown another method of locking the signatures of a group together and one in which a lock stitch is not employed. Figure 85 shows chain stitches 279 connecting adjacent signatures of a group. The chain stitch in the last signature 280 hangs free except for its engagement with the preceding loop. It will be understood that once the last signature 280 is removed from the signature group which may be done by pulling its loop out of the loop of the preceding signature there is nothing to prevent a continuation of this operation until all the signatures are separated. In order to prevent this a line of adhesive 281 is applied between the last signature 280 and the next adjacent signature 282. This will prevent these two signatures from becoming disengaged and the chain stitching will therefore be maintained intact. This line of glue may conveniently be applied to the signature 282 during the gathering operation and in Figure 84 is shown a simple device for applying this line of glue to the side of a signature while traveling forward under the influence of pin 13. 283 indicates a tank containing a body of adhesive 284 and provided with a cylinder 285 near its lower end from which leads a very small diameter pipe 286 terminating at a point above the signature placed upon vane 11. 287 is a plunger actuated by suitable means such as from rockshaft 8 that descends into cylinder 285 and forces a charge of adhesive through pipe 286 and thus on the signature in a line parallel to the folded lower edge of said signature. A valve 288 is provided which opens when plunger 287 descends and closes when it rises. The actuation of plunger 287 is so timed that the ejection of adhesive takes place only during the time that the signature is moving from one vane 11 into straddling position on the next vane 11, as previously described, and it will be understood that when the next signature such as 280 is delivered on top of the first signature such as 282 that said signatures will adhere by reason of the line of glue 281. In case it is merely desired to paste the two last signatures as 282 and 280 together the gluing attachment will be arranged adjacent to the second last hopper of the gathering machine. There may however be a glue attachment associated with each hopper if so desired, which attachment can be rendered ineffective at will in any suitable manner, so that the gathering machine may in effect also become a tipping machine. This is of considerable importance in this machine, although its use is not limited to a machine of this particular character, because it will be understood that it is impossible to convey single sheets along wires 18 and it is therefore necessary to either tip the singles before stacking the signatures in the hopper of the gath-

ering machine or to have the gathering machine automatically tip the singles to a signature having a folded back. In Figure 86 is shown a single sheet 289 which has thus been glued to signature 282 by means of paste line 281 and, in the present case since no lock stitch is employed, a second paste line 281^a glues the signature 280 to the single signature. In Figure 82 is shown a diagrammatic view in which the parts are distorted for the purpose of clearness, said diagrammatic view showing an adjustment that must be made in case one of the hoppers of the gathering machine contains singles. It will be apparent that if one of the hoppers of the signature gathering machine contains singles that are to be pasted to a folded signature that wire 18 leading from the next succeeding vane 11 would carry no signature to its needle in the sewing machine and that consequently there would be an idle needle in the sewing machine and there would be a missing stitch in a chain of stitches across the signature group. To remedy this condition it is necessary to cut out one of the vanes 11 which may be done in the following manner: 11^a, 11^b, 11^c, and 11^d represent a series of vanes in the gathering machine to which wires 18^a, 18^b, 18^c, and 18^d are connected, said wires reaching at the other end to the guides of needles 87. Let us assume that hoppers 5^b and 5^d contain folded signatures and that hopper 5^c contains singles. A folded signature fed from hopper 5^d and falling on vane 11^d will during its forward movement into the straddling position on vane 11^c receive the line of glue as indicated from pipe 286. After the signature reaches its proper position on vane 11^c a single leaf is fed from hopper 5^c on top of the upper surface of the first signature, and thus the product coming from hoppers 5^b and 5^c will be caused to travel over wire 18^c shown in dotted lines as being connected to vane 11^c. The signature coming from hopper 5^b will be placed on vane 11^b and will be brought into straddling position on vane 11^a and thence pass to the needles over wire 18^a. It will therefore be evident that no signature will be passing from vane 11^b over wire 18^b shown in dotted lines. It is therefore necessary to cut out, so to speak, the connection between vane 11^b and the needles. Wire 18^b as shown in dotted lines is therefore disconnected from 11^b and connected as indicated in full lines to vane 11^c and wire 18^c as indicated in dotted lines is disconnected from vane 11^c and connected to vane 11^d, etc. The result of this adjustment is that the idle needle which is bound to be produced will be the first needle of the series and may therefore be disregarded.

Figure 85 illustrates a further method that may be employed in binding books in accordance with the present invention. In that figure are shown two signature groups F and

G the signatures of each group being sewn together in a manner previously described there being however an idle needle between groups F and G so that the stitching is not carried across from one group to the other. This feature is of advantage when producing thin books of relatively few signatures because it admits of utilizing practically the entire capacity of the gathering and sewing machine with the exception of a single intervening hopper in the gathering machine and an idle needle in the sewing machine.

Referring to Figures 2, 7, 49, 50, 51, 52, 53 and 54 suitable means are provided for severing the threads between successive signature groups or signatures in tandem, in the present instance taking the following form: 290 indicates a spiral gear mounted on the main shaft 30 meshing with a corresponding spiral gear 291 on the end of shaft 292 supported in bracket 293 of the frame work and carrying at its outer end a sprocket pinion 294. 295 indicates a knife carrier rotatable with said shaft 292 and circumferentially adjustable of said shaft in the following manner: The knife carrier 295 is mounted loosely on shaft 292 but is connected by means of bolt 296 to an arm 297 keyed to shaft 292. Arm 297 is provided with an arcuate slot 298 through which bolt 296 extends said bolt being tapped into knife carrier 295. By loosening bolt 296 knife carrier 295 may be adjusted circumferentially of shaft 292. 299 indicates stationary knife members adjustably mounted on the knife carrier by means of T-blocks 300 which latter are slidably mounted in grooves 301 of the knife carrier and which are provided with elongated slots 302 through which pass bolts 303 tapped into the knife carrier. The T-blocks 300 are secured to the stationary knife members 299 by means of screws 304 or in any other suitable manner. Pivottally carried by ears 305, here shown as forming an integral part of the stationary knife member, are movable knife members 307 having angular extensions 308 pivotally connected to pintle 306 to which latter is connected a link 309 pivotally connected to yoke 310 slidably mounted in guides 311 on the knife carrier. At the lower end of this yoke is provided a cam roller 312 that engages with snail cam 313 mounted stationary on bracket 293. Rotation of shaft 292 will cause knife carrier 295 to rotate therewith and during this rotation stationary cam 313 will actuate the movable knife members and will sever the threads between successive signature groups or signatures in tandem. The knife carrier makes one revolution to each revolution of the main shaft and if we assume that the machine produces one book to each revolution of the main shaft and that books of different size will at different times be delivered past the cutting mechanism at different speeds that by circumferentially ad-

justing the knife carrier said knife may be made to reach its cutting position at the proper time during each cycle of the machine to properly cut the threads between successive 5 signature groups. As shown the cutting mechanism is located directly beneath the path of the signature group which travels between guides 226 and on an extension 314 of the sewing table. This extension 314 is provided with a slotted portion 315 to afford 10 access of the knives to the threads to be severed and said extension is provided with another slot 316 substantially at right angles to the first slot through which the open movable cutting blades may extend during rotation of the parts the action of cam 313 being of such a character that said movable cutting blades are in their open position when said 15 movable cutting blades pass through slot 316 and descend transversely between the books at the point where the slot 315 is located to thereby sever the threads. The direction of rotation of the cutter carrier is in the same 20 general direction as that of the advancing signature group.

As has been previously indicated, when the books pass out of the sewing zone, sewing conveyor 77 ceases to control the books and 25 they now come under the control of the delivery conveyor 317. This delivery conveyor is provided with pins 318 for acting on the books and said conveyor is driven from sprocket 319 passing at its other end over idler 320. Sprocket 319 is carried on an upright shaft 321 having at its lower end (Figures 30 55 and 56) a bevel pinion 322 that engages a bevel gear 323 mounted on shaft 324 having at its outer end a sprocket 325 driven from sprocket pinion 294 on the end of shaft 292. If the so-called packer box delivery is utilized 35 an oscillating packer blade 326 may be used, this packer blade being mounted on rock shaft 327 actuated by means of crank 328 having an arm 329 connected with arm 330 of rock shaft 327. Adjacent to said packer blade are oppositely sloping troughs 331 one book being delivered in one direction and the next book in the other direction. When this 40 form of delivery is used the relation of the gearing must be such that shaft 324 makes one revolution to each two revolutions of the main shaft or to each book delivered and this is the proportion shown in the present 45 instance; and in the present case, the shaft 321 of sprocket 319 being driven through the same chain of connections as the packer blade, said shaft 321 is given the speed of one revolution to each revolution of the main shaft, this relation being obtained by proportioning the bevel gears 322 and 323 in the ratio of one to two. In the present case and as a matter 50 of convenience a delivery roller 332 is conveniently mounted on shaft 324 and assists

in the ejection of the book from the delivery chain 317 to the trough.

It will of course be understood that when the sewing machine conveyor 77 has its speed changed and the positioning of its pins 78 adjusted to accommodate different sizes of books that the spacing of pins 318 on conveyor 317 and the speed thereof will likewise have to be adjusted. This may be done by having a number of sprockets such as 319 with a different number of teeth such as eight, ten and twelve, and as a matter of convenience different chains 317 with pins properly spaced may be used. If in order to get the proper spacing of the pins it is necessary to vary the length of the chain 317 then sprocket 320 may be adjusted in slot 333 (Figure 7) to compensate for such change in length.

In certain cases it may be desired to connect the sewing machine with a covering machine as indicated diagrammatically in Figure 1 where the end portion of a covering machine such as is disclosed in Patent 1,193,395 of August 1st, 1916, is shown. In that event a conveyor 334 will preferably be used having such speed and having its pins so spaced as to bring the books or signature groups back into a spacing, as between books, that they occupied when traveling under the influence of gathering machine conveyor 14; that is to say, the heads of the books will be equally spaced but the spacing between successive books will vary in accordance with the size of the books.

I claim:

1. A bookbinding machine comprising: means for advancing a signature group in an upright position with the folded backs of the signatures lowermost, a plurality of guides entering into the signature group at the advancing end thereof, one guide between the halves of each signature of the group, and a plurality of needles, one for each signature of the group, operating in the space produced by the guide and stitching each signature through the back.

2. A bookbinding machine comprising: means for advancing a signature group in an upright position with the folded backs of the signatures lowermost, a plurality of guides entering into the signature group at the advancing end thereof, one guide between the halves of each signature of the group, a plurality of needles, one for each signature of the group, operating in the space produced by the guide and stitching each signature through the back and, means for transferring a loop produced by the needle in one signature to a position beneath the next adjacent signature to admit of the stitch produced by the needle in said adjacent signature passing through the loop from the first signature.

3. In a bookbinding machine, a plurality of tapering signature guides, a plurality of needle bars, and a tapering slide connected

with each needle bar and extending into and forming a continuation of the signature guide.

4. In a bookbinding machine, a plurality of tapering signature guides, a plurality of needle bars, a tapering slide connected with each needle bar and extending into and forming a continuation of the signature guide and means for advancing, with the signatures thereof in an upright position and folded their folded backs lowermost, a signature group toward the tapered end of the signature guides to cause the latter to enter between the halves of each signature.

5. In a bookbinding machine, a tapering signature guide, a needle bar and a tapering slide mounted on the needle bar and extending into and forming a continuation of the tapering guide.

6. A bookbinding machine comprising means for advancing a signature group in an upright position with the folded backs of the signatures lowermost, the signatures of the group being in onset relation and a plurality of thread needles, one for each signature, for stitching through the folded back between the halves of each signature.

7. A bookbinding machine comprising: a gathering machine for gathering onset signatures with the halves of each signature slightly separated, a sewing machine for sewing the signatures together, means for feeding the onset signatures as a group from the gathering machine to the sewing machine, and guides, extending between the gathering and sewing machines, over which the signatures pass to maintain their halves slightly separated.

8. A bookbinding machine comprising: means for separating opposed halves of each of a plurality of signatures, means for associating the signatures side by side in an upright position with their halves slightly separated, and means for thereafter sewing the signatures together.

9. A bookbinding machine comprising: means for separating opposed halves of each of a plurality of signatures, means for associating the signatures side by side in an upright position with their backs lowermost and their halves slightly separated, and means for thereafter sewing the signatures together by stitching through the folded backs.

10. A bookbinding machine comprising: means for advancing a group of onset signatures in an upright position with the halves of each signature slightly separated and with their folded backs lowermost, and means for sewing the signatures together during their advancing movement by stitching through their folded backs.

11. A bookbinding machine comprising: means for advancing successive groups of signatures in an upright position with their folded backs lowermost, sewing needles pass-

ing through the folded backs of the signatures to sew the signatures of each group together and alined signatures of successive groups together, and means for separating the threads connecting alined signatures of adjacent groups.

12. A bookbinding machine comprising: infeed means delivering signature groups, the space between adjacent signature groups varying in accordance with the length of signatures, a sewing machine including a plurality of needles for sewing the signatures of a group together and for sewing alined signatures of successive groups together, and means intermediate the infeed means and sewing machine for spacing successive signature groups a less distance apart than the distance between successive stitches of a needle notwithstanding variations in length of the signatures.

13. A bookbinding machine comprising: infeed means delivering signature groups, the space between adjacent signature groups varying in accordance with the length of signatures, a sewing machine including a plurality of needles for sewing the signatures of a group together and for sewing alined signatures of successive groups together, means intermediate the infeed means and sewing machine for spacing successive signature groups a less distance apart than the distance between successive stitches of a needle notwithstanding variations in length of the signatures and means for varying the speed of the needles and the speed of travel of the signature groups passing through the sewing machine to thereby vary the number of stitches in accordance with the length of the signatures.

14. A bookbinding machine comprising: infeed, means delivering signature groups, the space between adjacent signature groups varying in accordance with the length of signatures, a sewing machine including a plurality of needles for sewing the signatures of a group together and for sewing alined signatures of successive groups together, means intermediate the infeed means and sewing machine for spacing successive signature groups a less distance apart than the distance between successive stitches of a needle notwithstanding variations in length of the signatures, means for varying the speed of the needles and the speed of travel of the signature groups passing through the sewing machine to thereby vary the number of stitches in accordance with the length of the signatures, a cutting mechanism for severing the threads connecting adjacent signature groups operating at a constant speed regardless of variations in length of the signatures composing the groups, and means for varying the point of cutting operation in the cycle of operations of said cutting mechanism in accord-

ance with the variations in length of the signatures composing the group.

15. A bookbinding machine comprising: a conveyor for feeding groups of signatures having folded backs through a sewing zone, a plurality of needles for piercing the folded backs of the signatures, a plurality of looping devices for transferring the loop produced by one needle in one signature to a point beneath an adjacent signature, and change speed mechanism for varying the speed of the needles, the speed of the conveyor and the speed of the looping devices.

16. A bookbinding machine comprising: a book conveyor for feeding books in an upright position with their folded backs lowermost through a sewing zone; a plurality of needles, one for each signature, for piercing the folded backs of the signatures, and a plurality of looping devices for transferring the loop produced by one needle in one signature to a point beneath an adjacent signature.

17. A bookbinding machine comprising: a book conveyor for feeding books in an upright position with their folded backs lowermost through a sewing zone; a plurality of needles for piercing the folded backs of the signatures, a plurality of looping devices for transferring the loop produced by one needle in one signature to a point beneath an adjacent signature, a lock needle for piercing the last signature of a group to lock the loop produced by the sewing needle in the last signature, and a shuttle for temporarily holding the lock loop produced by the lock needle.

18. A bookbinding machine comprising: a book conveyor for feeding books in an upright position with their folded backs lowermost through a sewing zone; a plurality of needles for piercing the folded backs of the signatures, a plurality of looping devices for transferring the loop produced by one needle in one signature to a point beneath an adjacent signature, a lock needle for piercing the last signature of a group to lock the loop produced by the sewing needle in the last signature, a shuttle for temporarily holding the lock loop produced by the lock needle, and a change speed mechanism for varying the speed of the needles, the speed of the conveyor, the speed of the looping devices and the frequency of operation of the lock shuttle.

19. A bookbinding machine comprising: infeed means delivering signature groups, the space between adjacent signature groups varying in accordance with the length of signatures, outfeed means for receiving successive signature groups spaced in accordance with the length of the signatures composing the group, a sewing machine located intermediate the infeed and outfeed means, said sewing machine including a plurality of needles, and conveying means for spacing

successive signature groups a less distance apart than the distance between successive stitches of a needle notwithstanding variations in length of signatures while said signature groups are passing through the sewing zone and for re-establishing the spaced relation varying with the length of the signatures of the group after said group emerges from the said sewing machine and before it reaches the outfeed means.

20. A bookbinding machine comprising: means for advancing a signature group in an upright position with the folded backs of the signatures lowermost, a plurality of guides entering into the signature group at the advancing end thereof, one guide between the halves of each signature of the group, a plurality of needles, one for each signature of the group, operating in the space produced by the guide and stitching each signature through the back, means for transferring a loop produced by the needle in one signature to a position beneath the next adjacent signature to admit of the stitch produced by the needle in said adjacent signature passing through the loop from the first signature, a locking needle for piercing the last signature of a group to lock the loop produced by the sewing needle in the last signature, and a shuttle for temporarily holding the lock loop produced by the lock needle.

21. A bookbinding machine comprising: a plurality of needles, a throat plate for supporting successive signature groups advancing in an upright position with their backs lowermost, a plurality of rotatable looping devices located beneath said throat plate, and a rotatable looper drive shaft for driving all the rotatable looping devices.

22. A bookbinding machine comprising: a plurality of needles, a throat plate for supporting successive signature groups advancing in an upright position with their backs lowermost, a plurality of looping devices located beneath said throat plate, a locking needle for piercing the last signature of the group to lock the loop produced by the sewing needle in the last signature, and a shuttle, for temporarily holding the lock loop produced by the lock needle, located adjacent the last looping device beneath the throat plate.

23. A bookbinding machine comprising: a plurality of needles, a throat plate for supporting successive signature groups advancing in an upright position with their backs lowermost, a plurality of looping devices located beneath said throat plate, a movable element forming a part of said throat plate, and means for vibrating said movable element between successive operations of the needles.

24. In a bookbinding machine, a needle bar carrier, two crank shafts supporting said needle bar carrier, pivotally supported arms

carrying at their free ends said crank shafts, and means for rotating said crank shafts.

25. In a bookbinding machine, a needle bar carrier, two crank shafts supporting said needle bar carrier, pivotally supported arms carrying at their free ends said crank shafts, and means for rotating said crank shafts from centers coincident with the pivotal supports of the arms.

10 26. In a bookbinding machine, a needle bar carrier, two crank shafts supporting said needle bar carrier, arms pivotally supported carrying at their free ends said crank shafts, an eccentric associated with one of said crank 15 shafts and anchored on a stationary part of the frame work, and means for rotating said crank shafts.

27. In a bookbinding machine a needle bar carrier, a plurality of crank shafts supporting said needle bar carrier, pivotally supported arms carrying at their free ends said crank shafts, gears on said crank shafts, gears, coincident with the centers of pivotal support of the arms, meshing with the gears 25 on said crank shafts, a looper drive shaft, means for transmitting motion to said looper drive shaft from one of the gears mounted coincident with the pivotal support of one of the arms.

30 28. Sewing means comprising: a threaded needle to pierce the folded back of a signature, a looper to bring a loop of the thread of said needle in the plane of the folded back of a second signature onset with respect to the 35 first signature, a second threaded needle to pierce the folded back of said second signature and to pass through the thread loop of the first needle, and a support to support the signatures in onset relation with respect to each other.

40 29. Sewing means comprising: a threaded needle to pierce the folded back of a signature a plurality of times to produce longitudinal stitches therein, a looper to bring a 45 loop of the thread of said needle, after each piercing, in the plane of the folded back of a second signature onset with respect to the first signature, a second threaded needle to pierce the folded back of said second signature a plurality of times to produce longitudinal 50 stitches therein and to pass through the thread loops of the first signature, and a support to support the signatures in onset relation with respect to each other.

55 30. Sewing means comprising: a threaded needle to pierce the folded back of a traveling signature a plurality of times to produce longitudinal 60 stitches therein, a looper to bring a loop of the thread of said needle, after each piercing, in the plane of the folded back of a second traveling signature onset with respect to the first signature, a second threaded needle to pierce the folded back of said second traveling signature a plurality of times to 65 produce longitudinal stitches therein and to

pass through the thread loops of the first signature, a support to support the signatures in onset relation with respect to each other, and feeding devices for advancing the signatures.

70 31. Sewing means comprising: a threaded needle to pierce the folded backs of a plurality of signatures arranged in tandem, each signature being pierced a plurality of times to produce a plurality of longitudinal stitches 75 therein and a stitch between adjacent signatures in tandem, a looper to bring a loop of the thread of said needle, after each piercing, in the plane of the folded backs of a second plurality of signatures also arranged in tandem and in onset relation to the first plurality of signatures, a second threaded needle to pierce the folded backs of the second plurality of signatures, each signature of said second plurality of signatures in tandem being pierced a plurality of times to produce a plurality of longitudinal stitches therein, a stitch between adjacent signatures in tandem 80 and to pass through the thread loops of the first-mentioned plurality of signatures, and a support to support the two pluralities of signatures in onset relation.

85 32. Sewing means comprising: a threaded needle to pierce the folded backs of a plurality of signatures arranged in tandem, each signature being pierced a plurality of times to produce a plurality of longitudinal stitches 90 therein and a stitch between adjacent signatures in tandem, a looper to bring a loop of the thread of said needle, after each piercing, in the plane of the folded backs of a second plurality of signatures also arranged in tandem and in onset relation to the first plurality of signatures, a second threaded needle to pierce the folded backs of the second 95 plurality of signatures, each signature of said second plurality of signatures in tandem being pierced a plurality of times to produce a plurality of longitudinal stitches therein, a stitch between adjacent signatures in tandem 100 and to pass through the thread loops of the first-mentioned plurality of signatures, a support to support the two pluralities of signatures in onset relation, and a cutting device for severing the thread stitch between adjacent signatures in tandem.

105 33. Sewing means comprising: a threaded needle to pierce the folded backs of a plurality of signatures arranged in tandem, each signature being pierced a plurality of times to 110 produce a plurality of longitudinal stitches therein and a stitch between adjacent signatures in tandem, a looper to bring a loop of the thread of said needle, after each piercing, in the plane of the folded backs of a second plurality of signatures also arranged in tandem and in onset relation to the first plurality of signatures, a second threaded needle to 115 pierce the folded backs of the second plurality of signatures, each signature of said 120 second plurality of signatures in tandem being pierced a plurality of times to produce a plurality of longitudinal stitches therein, a stitch between adjacent signatures in tandem and to pass through the thread loops of the first-mentioned plurality of signatures, a support to support the two pluralities of signatures in onset relation, and a cutting device for severing the thread stitch between adjacent signatures in tandem.

second plurality of signatures in tandem being pierced a plurality of times to produce a plurality of longitudinal stitches therein, a stitch between adjacent signatures in tandem and to pass through the thread loops of the first-mentioned plurality of signatures, a support to support the two pluralities of signatures in onset relation, and feeding devices to advance both pluralities of signatures in spaced relation, the spacing between adjacent signatures in tandem being less than the length of the stitch connecting said adjacent signatures in tandem.

34. Sewing means comprising: a threaded needle to pierce the folded backs of a plurality of signatures arranged in tandem, each signature being pierced a plurality of times to produce a plurality of longitudinal stitches therein and a stitch between adjacent signatures in tandem, a looper to bring a loop of the thread of said needle, after each piercing, in the plane of the folded backs of a second plurality of signatures also arranged in tandem and in onset relation to the first plurality of signatures, a second threaded needle to pierce the folded backs of the second plurality of signatures, each signature of said second plurality of signatures in tandem being pierced a plurality of times to produce a plurality of longitudinal stitches therein, a stitch between adjacent signatures in tandem and to pass through the thread loops of the first-mentioned plurality of signatures, a support to support the two pluralities of signatures in onset relation, feeding devices to advance both pluralities of signatures in spaced relation, the spacing between adjacent signatures in tandem being less than the length of the stitch connecting said adjacent signatures in tandem, and a cutting device for severing the thread stitch between adjacent signatures in tandem.

35. Sewing means comprising: a threaded needle to pierce the folded backs of a procession of signatures advancing in tandem, each signature being pierced a plurality of times to produce a plurality of longitudinal stitches therein and a stitch between adjacent signatures in tandem, a looper to bring a loop of the thread of said needle, after each piercing, in the plane of the folded backs of a second procession of signatures advancing in tandem and in onset relation to the first procession of signatures, a second threaded needle to pierce the folded backs of the second procession of signatures, each signature of said second procession being pierced a plurality of times to produce a plurality of longitudinal stitches therein, a stitch between adjacent signatures in tandem, and to pass through the thread loops of the first-mentioned procession of signatures, and a support to support the signatures of the two processions in onset relation.

36. Sewing means comprising: a threaded

needle to pierce the folded backs of a procession of signatures advancing in tandem, each signature being pierced a plurality of times to produce a plurality of longitudinal stitches therein and a stitch between adjacent signatures in tandem, a looper to bring a loop of the thread of said needle, after each piercing, in the plane of the folded backs of a second procession of signatures advancing in tandem and in onset relation to the first procession of signatures, a second threaded needle to pierce the folded backs of the second procession of signatures, each signature of said second procession being pierced a plurality of times to produce a plurality of longitudinal stitches therein, a stitch between adjacent signatures in tandem, and to pass through the thread loops of the first-mentioned procession of signatures, a support to support the signatures of the two processions in onset relation, and a cutting device for severing the thread stitch between adjacent signatures in tandem.

37. Sewing means comprising: a threaded needle to pierce the folded backs of a procession of signatures advancing in tandem, each signature being pierced a plurality of times to produce a plurality of longitudinal stitches therein and a stitch between adjacent signatures in tandem, a looper to bring a loop of the thread of said needle, after each piercing, in the plane of the folded backs of a second procession of signatures advancing in tandem and in onset relation to the first procession of signatures, a second threaded needle to pierce the folded backs of the second procession of signatures, each signature of said second procession being pierced a plurality of times to produce a plurality of longitudinal stitches therein, a stitch between adjacent signatures in tandem, and to pass through the thread loops of the first-mentioned procession of signatures, a support to support signatures of the two processions in onset relation, and feeding devices to advance both processions of signatures in spaced relation, the spacing between adjacent signatures in tandem being less than the length of the stitch connecting said adjacent signatures in tandem.

38. Sewing means comprising: a threaded needle to pierce the folded backs of a procession of signatures advancing in tandem, each signature being pierced a plurality of times to produce a plurality of longitudinal stitches therein and a stitch between adjacent signatures in tandem, a looper to bring a loop of the thread of said needle, after each piercing, in the plane of the folded backs of a second procession of signatures advancing in tandem and in onset relation to the first procession of signatures, a second threaded needle to pierce the folded backs of the second procession of signatures, each signature of said second procession being pierced a plurality of times to produce a plurality of longitudinal

nal stitches therein, a stitch between adjacent signatures in tandem, and to pass through the thread loops of the first-mentioned procession of signatures, a support to support the signatures of the two processions in onset relation, feeding devices to advance both processions of signatures in spaced relation, the spacing between adjacent signatures in tandem being less than the length of the 5 stitch connecting said adjacent signatures in tandem, and a cutting device for severing the thread stitch between adjacent signatures in tandem.

39. Sewing means comprising: a threaded 15 needle to pierce the folded back of a signature, a looper to bring a loop of the thread of said needle in the plane of the folded back of a second signature onset with respect to the first signature, a second threaded needle to 20 pierce the folded back of said second signature and to pass through the thread loop of the first needle, a support to support the signatures in onset relation with respect to each other, and a threaded lock needle for piercing 25 the second signature to lock the loop produced by the second threaded needle.

40. Sewing means comprising: a threaded needle to pierce the folded back of a signature, a looper to bring a loop of the thread 30 of said needle in the plane of the folded back of a second signature onset with respect to the first signature, a second threaded needle to pierce the folded back of said second signature and to pass through the thread loop of 35 the first needle, a support to support the signatures in onset relation with respect to each other, a threaded lock needle for piercing the second signature to lock the loop produced by the second threaded needle, and a shuttle for 40 temporarily holding the lock loop produced by the lock needle.

41. Sewing means comprising: a threaded needle to pierce the folded back of a signature a plurality of times to produce longitudinal 45 stitches therein, a looper to bring a loop of the thread of said needle, after each piercing, in the plane of the folded back of a second signature onset with respect to the first signature, a second threaded needle to 50 pierce the folded back of said second signature a plurality of times to produce longitudinal stitches therein and to pass through the thread loops of the first signature, a support to support the signatures in onset 55 relation with respect to each other, and change speed mechanism for varying the speed of the needles, the speed of the signature feeding devices and the speed of the looper.

60 42. Sewing means comprising: a threaded needle to pierce the folded back of a signature a plurality of times to produce longitudinal 65 stitches therein, a looper to bring a loop of the thread of said needle, after each piercing, in the plane of the folded back of each

a second signature onset with respect to the first signature, a second threaded needle to pierce the folded back of said second signature a plurality of times to produce longitudinal 70 stitches therein and to pass through the thread loops of the first signature, a support to support the signatures in onset relation with respect to each other, a threaded lock needle for piercing the second signature to lock the loop produced by the second threaded needle, a shuttle for temporarily holding the lock loop produced by the lock needle, and a change speed mechanism for varying the speed of the needles, the speed 75 of the signature feeding devices, the speed of the looper and the frequency of operation of the lock shuttle.

43. A bookbinding machine comprising: means for advancing a group of folded signatures, a plurality of guides entering into the signature group, one guide between the halves of each signature of the group, and a plurality of needles, one for each signature of the group, operating in the space produced 80 by the guide and stitching each signature through the folded back.

44. A bookbinding machine comprising: means for advancing a group of folded signatures, a plurality of guides entering into the signature group, one guide between the halves of each signature of the group, a plurality of needles, one for each signature of the group, operating in the space produced 85 by the guide and stitching each signature through the folded back, and means for transferring a loop produced by the needle in one signature to a position in line with the back of an adjacent signature to admit of the 90 stitch produced by the needle in said adjacent signature passing through the loop from the first signature.

45. A bookbinding machine comprising: means for advancing a group of onset signatures having folded backs with the halves 95 of each signature slightly separated, and means for sewing the signatures together during their advancing movement by stitching through their folded backs.

46. A bookbinding machine comprising: means for advancing successive groups of signatures having folded backs, sewing needles passing through the folded backs of the signatures to sew the signatures of each group together and alined signatures of successive groups together, and means for separating the threads connecting alined signatures of successive groups.

47. A bookbinding machine comprising: means for advancing a group of folded signatures, the signatures of the group being in onset relation, and a plurality of thread needles, one for each signature, for stitching through the folded back between the halves of each signature.

48. A bookbinding machine comprising: means for advancing a group of folded signatures, the signatures of the group being in onset relation, a plurality of thread needles, one for each signature, for stitching through the folded back between the halves of each signature, and a plurality of looping devices for transferring a loop produced by the needle in one signature to a position in line with the back of an adjacent signature to admit of the stitch produced by the needle in said adjacent signature passing through the loop from the first signature. 5
49. A bookbinding machine comprising: means for separating opposed halves of each of a plurality of signatures, means for associating the signatures side by side with their halves slightly separated, and means for thereafter sewing the signatures together. 10
50. A bookbinding machine comprising: means for separating opposed halves of each of a plurality of signatures, means for associating the plurality of signatures side by side in an upright position with their halves slightly separated, means for advancing the signatures thus associated as a group in an upright position with their folded backs lowermost, and means for sewing the signatures together by stitching through their 25 folded backs. 30
51. A bookbinding machine comprising: means for separating opposed halves of each of a plurality of signatures, means for piling the plurality of signatures with their halves slightly separated, means for advancing the signatures thus piled as a group in an upright position with their folded backs lowermost, and means for sewing the signatures together by stitching through their folded backs. 35
52. A bookbinding machine comprising: means for insetting a separating element between the halves of each of a plurality of signatures, means for onsetting the plurality of signatures with the separating elements inset, means for advancing the onset signatures as a group in an upright position with their folded backs lowermost, and means for sewing the signatures together by stitching through their folded backs. 40
53. A bookbinding machine comprising: means for advancing a group of onset signatures in an upright position with the halves of each signature slightly separated and with its folded back lowermost, and means for sewing the signatures together by stitching through their folded backs. 45
54. A bookbinding machine comprising: means for advancing successive groups of signatures in an upright position with their folded backs lowermost, means for stitching through the folded back of the signatures to thereby sew the signatures of each group together and alined signatures of adjacent groups together, and means for severing the threads connecting alined signatures of adjacent groups. 50
55. A bookbinding machine comprising: means for gathering signatures into multiple onset groups, each group consisting of onset signatures, and means for sewing together the signatures of each multiple group simultaneously to produce multiple independent books. 70
56. A sewing machine comprising: means for supporting a plurality of signatures in onset relation, a gang of reciprocating needles, one for each signature, and means for bringing the signatures and needles into such relation that the needles act sequentially on successively onset signatures. 80
57. A sewing machine comprising: means for supporting a plurality of signatures in onset relation, a gang of reciprocating needles, one for each signature, and means for bringing the signatures and needles obliquely into sewing relation so that successive needles act sequentially on successively onset signatures. 85
58. A sewing machine comprising: means for supporting a plurality of signatures in onset relation, a gang of reciprocating needles, one for each signature, arranged in a straight line one behind the other, and means for feeding the signatures as a group obliquely with respect to the line of needles so that the needles act sequentially on successively onset signatures. 90
59. A sewing machine comprising: a sewing table for supporting a plurality of folded signatures in upright position and onset relation with their folded backs lowermost, a throat plate in said sewing table, conveying means for advancing the signatures over the sewing table and throat plate, a plurality of threaded needles, one for each signature, above the throat plate to enter between the halves of the signatures, and looping devices below the throat plate. 95
60. A sewing machine comprising: a plurality of reciprocating thread needles, a guide associated with each needle to enter between the halves of a folded signature, and conveying means to feed a group of folded signatures in onset relation to the guides and needles. 100
61. A book stitching machine, comprising in combination a frame, a sewing head mounted upon said frame, a conveyor adapted to transport the books underneath the sewing head, and an automatic feeding device adapted to move the book onto the automatic conveyor. 105
62. A book stitching machine, comprising in combination a frame, a sewing head mounted upon said frame, a conveyor adapted to transport the books underneath the sewing 115
